ATTORNEYS.

UNITED STATES PATENT OFFICE.

ARDIE WILLIAMS, OF LOS ANGELES, CALIFORNIA, ASSIGNOR OF ONE-HALF TO EDWIN A. PARKFORD AND HARRY BOYER, BOTH OF LOS ANGELES, CALIFORNIA.

DESIGN FOR A WIND-DEFLECTOR.

57,804.

Specification for Design.

Patented May 3, 1921.

Application filed April 29, 1920. Serial No. 377,718. Term of patent 7 years.

To all whom it may concern:

Be it known that I, ARDIE WILLIAMS, a citizen of the United States, residing at Los Angeles, county of Los Angeles, and State of California, have invented a new, original, and ornamental Design for Wind-Deflectors, of which the following is a specification, reference being had to the accompanying drawing, forming a part thereof.

Figure 1 is a front elevation of a wind deflector, showing my new design.

Fig. 2 is a side view thereof, and

Fig. 3 is a plan view thereof.

I claim:

The ornamental design for a wind deflector as shown.

ARDIE WILLIAMS.
